UNITED STATES PATENT OFFICE.

LOUIS HORVATH AND THOMAS J. BLACKBURN, OF MINGO JUNCTION, OHIO.

SWITCH-FROG.

1,342,332.

Specification of Letters Patent.

Patented June 1, 1920.

Application filed March 26, 1919. Serial No. 285,215.

To all whom it may concern:

Be it known that we, LOUIS HORVATH and THOMAS J. BLACKBURN, citizens of the United States of America, and residents of 5 Mingo Junction, county of Jefferson, and State of Ohio, have invented certain new and useful Improvements in Switch-Frogs, of which the following is a specification.

This invention relates broadly to railway 10 switch frogs, and it has for its principal object to provide a frog, designed primarily for use in mines or trackways in which rails of light weight are employed, which is constituted of a single metal casting adapted 15 to receive the ends of the rails and to support the latter in such manner that they are permanently maintained in a common plane, thereby obviating the objections common to the usual forms of frogs which permit one 20 of adjacent ends of alined rails at the frog to sink below the level of the other.

A further object is to provide a frog construction whereby the ends of alined rails are secured in permanently alined relation.

25 A still further object is to provide a frog which may be quickly and conveniently applied in position.

With these and other objects in view, the invention resides in the features of construction which will hereinafter be fully described, reference being had to the accompanying drawings, in which—

Figure 1 is a top plan view of the invention;

35 Fig. 2 is a side elevation of the same; and Fig. 3 is a section on line 3—3, Fig. 1.

Referring to said drawings, in which like designating characters distinguish like parts throughout the several views.

40 1 indicates a flat base or bed-plate adapted for mounting upon the usual crossties in any appropriate manner, suitable recesses or notches 2 for the reception of attaching spikes being preferably provided at suitable points about the outer edge of said base, as shown. Provided in the top face of the base 1 are four sunken seats 3 for the reception of the ends of rails 9, said seats being arranged in two alined pairs with the center lines of said pairs crossing each other at an angle predetermined to correspond with that of the switch with the main track, or with that of one cross-over track with the other, as the case may be.

45 55 Formed integral with the bed-plate 1 and

disposed at one side of and in overhanging relation to each of the seats 3 is an angle member 4 the contour of which corresponds substantially with that of a common form of angle-bar, or fish plate, and which is designed to have a rail end indicated in Fig. 3, a detachable angle-bar 5 being seated upon the opposite side of said rail and secured in seated relation to said plate by means of spikes driven into place through 60 one or more apertures 6 provided therefor in said bed-plate.

The relatively inclined angle members 4 at one end of the bed-plate have their inner ends meeting integral upright webs 7 which 70 have their upper edges disposed on a higher plane than said members, or on the same plane as that of the tread surfaces of rails mounted in place against said members. Said webs are of angular form, one portion 75 7^a of each constituting a tread for the wheels of cars and being disposed in alined relation to the adjacent rails, while the other portion 7^b of each constitutes a guard tongue. Said tongues are divergently in- 80 clined and each is located at a spaced distance from the adjacent lateral edge of an interposed acute-angled frog-point 8, integral with the bed-plate, having its upper face in the same plane as that of the treads 85 of the rails which seat upon the bed-plate with their ends in abutting relation to the outer end thereof. Said lateral edges of said frog point are disposed in direct alinement with the inner edges of the treads 7^a 90 of the webs 7, as shown.

The seats 3 formed in the bed-plate have those edges thereof opposite to the angle members 4 inclined slightly out of parallel relation to said members, as shown in Fig. 95 1, to permit of slight variation of the angle at which the rail end may lie with respect to the tread portions of the webs 7 and of the frog point 8.

What is claimed is—

A one-piece railway frog comprising a bed-plate having angle-members formed on the top face thereof and adapted to receive rail ends thereagainst, said members being arranged in two alined pairs the projected 105 lines of which cross each other, angular webs formed on said bedplate having portions constituting treads meeting the angle members located at one end of said bed plate, and having other portions constitut- 110

ing divergently inclined guards, a frog point having its outer end meeting the angle members on the opposite end of said bed plate and having its point located between and 5 at a spaced distance from said guards, each lateral edge of said frog point being in alinement with the inner edge of the tread portion of the opposite web, said bed plate being plain and flat and having a width approxi- 10 mately its length and also having the

aforesaid elements rising directly from the face thereof.

In testimony whereof we affix our signatures in presence of two witnesses.

LOUIS HORVATH.
THOMAS J. BLACKBURN.
